William J. Gribbens, St. Paul, Minn., assignor, by mesne assignments, to Plastics, Inc., St. Paul, Minn., a corporation of Delaware

Filed Mar. 14, 1968, Ser. No. 10,970

Term of patent 14 years

Int. Cl. D7—01

U.S. Cl. D36—8

FIG. 1

FIG. 2

FIGURE 1 is a perspective view of a drinking tumbler, showing my new design;

FIGURE 2 is an elevational view a portion being broken away to show a portion of the interior thereof.

The characteristic feature of the design resides in the roughened inner surface of the indented bottom portion.

I claim:

The ornamental design for a drinking tumbler, as shown and described.
